UNITED STATES PATENT OFFICE.

PHILIP WUEST, JR., OF PHILADELPHIA, PENNSYLVANIA, ASSIGNOR TO THE AUTOMATIC PIANO ACTION COMPANY, OF PHILADELPHIA, PENNSYLVANIA, A CORPORATION OF NEW JERSEY.

AUTOMATIC MUSICAL INSTRUMENT.

1,111,122.

Specification of Letters Patent. Patented Sept. 22, 1914.

Application filed May 18, 1908. Serial No. 433,416.

To all whom it may concern:

Be it known that I, PHILIP WUEST, Jr., of Philadelphia, in the county of Philadelphia and State of Pennsylvania, have invented certain new and useful Improvements in Automatic Musical Instruments, whereof the following is a specification, reference being had to the accompanying drawings.

In Letters Patent of the United States No. 847,534, dated March 19th, 1907, I have shown and described a damping device adapted to be combined with a piano, and having for its purpose the variation of the effect of the playing mechanism upon certain of the strings independently of the others. Although said device is susceptible of employment in connection with a piano whose hammers are automatically actuated, it requires the personal control of the operator, who must shift it, manually or by means of a pedal, at the proper intervals.

The object of my present invention is to provide a damping device for automatically varying the effect of the playing mechanism upon certain groups of strings independently of the others, in a piano whose hammers are automatically actuated by the well known pneumatic system, the control of the damping device being attained by means of the perforated sheet and tracker bar, which are employed for the actual playing.

In the accompanying drawings, Figure I, represents a partial front elevation of the interior of a piano casing, to which my invention has been applied, the details of the playing mechanism proper being omitted for the sake of clearness. Fig. II, is a vertical transverse section on the line II, II, of Fig. I, showing the location of the hammers with relation to the damping device. Fig. III, is a top or plan view of the chest containing the pneumatic mechanism, which directly actuates the damping device. Fig. IV, is a vertical longitudinal section through said chest on the line IV, IV, of Fig. III. Figs. V, and VI, are respectively transverse vertical sections on the lines V, V, and VI, VI, looking in the direction of the arrows in Fig. III. Fig. VII, is a vertical transverse section on the line VII, VII, in Fig. III. Fig. VIII, is a diagrammatic view of a portion of the perforated sheet and tracker bar, illustrating the manner in which the

damping device is controlled by means of 55 said sheet.

As in my said patent above referred to, the damping device for varying the effect of the hammer blows upon certain of the strings includes a pendent strip of suitable material, such as felt or soft leather, which normally is supported clear of the striking line of the hammers, but which can be shifted so as to be temporarily interposed between the hammers and the selected strings. The general object of such a device is to subdue the sound of certain notes or groups of notes without affecting others, as in the case of an accompaniment and a solo. Practically speaking, this purpose is sufficiently attained 65 by dividing the strings into two groups, one of which preferably corresponds with the bass notes extending to the commencement of the treble clef, the other corresponding with the notes from the lowest of 75 the treble clef to the upper limit of the register. Hence while my invention is not necessarily limited to a subdivision into two groups, I have thus shown it in the accompanying drawings, and will describe it as 80 thus embodied.

Referring now to the drawings, 1, represents the casing of an ordinary upright piano, whose hammers 2, (see Fig. II) are adapted to be actuated by pneumatics controlled through a tracker bar 3, by means of a perforated sheet 4, shown in dotted lines in Fig. II. Said pneumatic playing mechanism being well understood, it is not deemed necessary to refer thereto in detail, beyond 85 stating that the hammers 2, are controlled by means of what may be termed the main set of perforations 5, in the sheet 4, (see Fig. VIII). In front of the strings 6, I provide damping strips, in this instance two in number, indicated at 7, and 8, respectively, the strip 8, being indicated in its raised position, where its lower edge is above the striking line of the hammers 2, while the strip 7, is indicated as in its lower position, where it is 95 interposed between the hammers 2, and the strings 6. In the instance selected for illustration, this lower position is the normal one, when the damping devices are thrown into operative relation to the hammers. The 100 strip 7, corresponds in lateral extent, with the group of strings constituting the bass, as above mentioned, while the strip 8, corre-

sponds in lateral extent with the group of strings constituting the treble. The strips 7, and 8, are suspended from light frames 10, and 11, respectively, said frames being mounted upon pivoted arms 12, 13, and 14, 15, respectively. A convenient pivotal bearing for said arms is provided by means of a rod 17, which, in this instance, extends the whole transverse length of the instrument, and which is rigidly supported at its ends in brackets 18, 19, secured to the casing, and at intermediate points by brackets 20, 21, secured to the frame.

The arm 12, of the frame 10, and the arm 14, of the frame 11, are prolonged beyond their pivotal bearings upon the rod 17, so as to constitute levers, by means of which the frames may be independently actuated, so as to raise and lower the damping strips 20, respectively carried thereby. Said arms 12, and 14, are adapted to be moved by the pneumatics 28, and 30, to which they are adjustably attached by the rods 27, and 29, respectively.

The pneumatics 28, and 30, are secured to the vacuum chest 26, and their operation is controlled as will be hereinafter described.

A spring 24, is attached to the lever 14, between its pivotal point, and the point of attachment to the frame 11, as shown in Fig. II, and the other end of said spring is fastened to the hook 25, mounted upon the chest 26. A similar spring is attached in like relation to the lever 12. These springs lift the damping devices above the striking level of the hammers 2, when the pneumatics are in free communication with the atmosphere.

The chest 26, is in communication with the exhausting bellows (not shown), by means of the tubes 31, and 33, which have interposed between them a valve box 32. Said valve box 32, is of well known construction and hence need not be shown in detail. Its object, however, is to allow the communication between the exhausting bellows and the chest 26, to be cut off and hence to permit the damping device to remain inactive, at the will of the operator. The valve in box 32, is controlled by the slide valve 36, which is connected with a hand lever 37, by means of a link 38. Said slide valve 36, is interposed between the tube 40, which leads to the valve box 32, and the tube 41, which is connected with the exhausting bellows, and it is obvious that by manipulating lever 37, the exhaust through the tube 40, may be cut off so as to close the valve in box 32, and in turn cut off the exhaust through tube 33, and chest 26, and therefore cause the actuating mechanism of the damping mechanism to become idle.

Referring now to Figs. III, and IV, it will be seen that the chest 26, is divided into two compartments 50, and 51, which are in

communication with the chambers 52, and 53, through the ports 54, and 55, respectively. Said chambers 52, and 53, are in turn connected by means of a tube 56. A nipple 58, connects the chamber 52, with the tube 33, and it will be readily seen that the chambers 50, and 51, are directly connected with the exhaust 33, when the valves 60, and 61, are open, which is always the case, as they have no direct relation to the automatic control of the damping devices, but are for a purpose which will hereinafter be described.

As shown in Fig. VIII, two auxiliary ducts 70, and 71, are located on the tracker bar 3, one on each end of the series of main ducts which control the actual playing mechanism. The music sheet 4, is also provided with a series of auxiliary apertures 72, and 73, arranged along its edges, and adapted to register with the ducts 70, and 71, respectively. The damping device for the bass is controlled by the apertures 72, and that for the treble by the apertures 73; hence when it is desired to accent a note or chord, on either the bass or treble, one of these auxiliary perforations is placed slightly in advance of the transverse line which would correspond with the position of the main perforations which control the playing of such note or chord, assuming, of course, that the auxiliary openings of the tracker bar are in line with the note controlling apertures, as shown in this instance.

Referring to Fig. I, tubes 75, and 76, lead from the duct 70, and 71, respectively to the nipples 77, and 78, which are located at the ends of the channels 79, and 80, located in the wall 81, of the chest 26. Said channels 79, and 80, communicate with the circular recesses 83, and 84, across which are spanned the diaphragms 85, and 86, respectively. The bleed holes 105, and 106, extend from the chambers 50, and 51, to the circular recesses 83, and 84, respectively, and their function will be described later. Above said diaphragms and adapted to be engaged thereby, are suspended the pins 87, and 88, carrying the valve disks 89, and 90, which are covered with leather on both ends and play loosely in the openings 91, and 92, in the cover 93, of the chest 26. The opening 91, is closed at the top by a disk 95, having an aperture 96, and at the bottom by a similar disk 97, also having an aperture 98. The valve pin 87, fits loosely in the apertures 95, and 98, and the disks 95, and 97, form seats for valve 89, which is therefore double acting. The opening 92, is also inclosed at its ends by the disks 100, and 101, having apertures 102, and 103, over which the valve disk 90, plays. The openings 91, and 92, communicate with the recesses 110, and 111, through the channels 112, and 113, respectively. The recesses 110, and 111, are

spanned by the diaphragms 115, and 116, above which are suspended the valve stems 118, and 120, whose lower ends are bent in the form of rings, and adapted to be engaged by said diaphragms. Two circular openings 122, and 123, are located in the cover 93, of the chest 26, above the recesses 110, and 111.

To the valve stem 118, are adjustably secured two valve disks 125, and 126, which play in the opening 122, and over the annular openings in the plates 128, and 129, secured to the cover 93, and span the ends of opening 122, and having tongues 130, and 131, respectively to support and guide the stem 118. The stem 120, is also provided with valve disks 135, and 136, adjustably secured thereto, and which play over the annular openings in the plates 137, and 138, which span the ends of the opening 123, and are provided with tongues 140, and 141, respectively, for supporting and guiding said valve stem 120. The openings 122, and 123, are in communication with the bellows 28, and 30, through the channels 150, and 151, respectively.

Normally, the damping devices are both raised, but for convenience of illustration, one of them has been shown in the lowered position and the operation of the device will now be described.

As shown in Fig. VIII, the music sheet 4, covers the aperture 70. The pressure on both sides of the diaphragm 85 (Fig. VI), is equalized by means of the bleed hole 105, and therefore the diaphragm is kept lowered by its own weight. The valve disk 89, over the opening 98, in the disk 97, also drops, thereby allowing atmospheric pressure to enter through the opening 96, in the disk 95, and channel 112, to the circular recess 110. The diaphragm 115, is therefore raised and with it the stem 118, thereby opening the valve 126, and closing the valve 125. The pneumatic 28, is now in communication with the chamber 50, through channel 150, and hence collapsed due to the vacuum therein. The collapse of said pneumatic 28, causes the left hand end of lever 12, to be raised and its right hand end lowered, against the tension of spring 24, thus causing the damping device 7, to again fall into the path of the hammers of the bass portion of the piano, thus subduing the sound of the note or chord, that may be struck at that instant.

As the two sections of the device are identical, it will be convenient to describe the opposite state of affairs on the treble side, which explanation will therefore also hold good for the bass, when an aperture registers with the duct for raising its damping device.

The aperture 73, in sheet 4, registers with the duct 71, thus allowing the atmospheric

pressure to enter through the tube 76, and channel 80, to the circular recess 84, (Fig. V); thereby raising the diaphragm 86, and with it the valve 90, hence closing the opening 102, and establishing communication between the chamber 51, and recess 111, through the channel 113, and valve opening 103, in disk 101. The pressure on both sides of the diaphragm 116, is now equalized and it therefore drops by its own weight. The weight of the stem 120, with its disks 135, and 136, causes it to drop thus closing the opening in plate 138, and allowing atmospheric pressure to enter the pneumatic 30, through the opening in plate 137, and channel 123. The pneumatic 30, is now opened under the tension of spring 24, thus pulling up the right hand end of lever 14, and with it the damping device 8, thereby allowing the hammers in the treble section to strike the strings without the interposed damping strip. It will be evident, therefore, that I have provided a pneumatic actuating mechanism for shifting the damping device, which actuating mechanism includes main valves 90 and that the main valves are controlled also by a pneumatic actuating means, which includes auxiliary valves and that the auxiliary valves are controlled pneumatically by the music sheet.

In the particular instance shown in the drawings, the treble portion is being accentuated and the bass is subdued for the purpose of accompaniment.

Reference has above been made to the valves 60, and 61, as having no direct relation to the automatic control of the damping devices. The purpose of these valves will now be described. Under some circumstances, as for instance, where the perforated roll or music sheet is not provided with the necessary auxiliary perforations, the operator may desire to employ the damping devices by manual control.

As hereinbefore stated, the pneumatics 28, and 30, are normally collapsed, and this is the case when the ducts 70 and 71, are covered by the music sheet 4, hence if said sheet were not provided with the auxiliary apertures, the dampers would never be raised, practically making the device useless, and the conditions assumed by both sections would be those shown as to the bass section in Fig. VI. These valve disks 60, and 61, are adjustably mounted on the stems 160, and 161, which are suspended over the diaphragms 162, and 163, spanned over the circular recesses 165, and 166, in the bottom of the valve chambers 52, and 53, respectively. Channels 168, and 169, lead from recesses 165, and 166, and terminate in the nipples 170, 171, at the ends of the chest 26. Tubes 176, and 177, may be employed to connect the nipples 170, and 171, with the valves 178, and 179, which could be controlled by

hand levers 180, and 181, respectively as shown in dotted lines in Fig. I. As both these auxiliary valves 60, and 61, are the same, it will suffice to explain the action of one of them. The valve 60, in Fig. VII, is open on account of the circular recess 165, being in communication with the atmosphere through duct 168, and nipple 170. The diaphragm 162, is therefore raised by the atmospheric pressure, and with it the stem 160, and disk 60, thus opening the port 55, and affording communication between chambers 50, and 52. If the valve 178, were now closed by shifting lever 180, the pressure on both sides of the diaphragm 162, would be equalized by the bleed hole 175, thus the stem 160, would drop by its own weight and the disk 60, would then cover the port 55, and hence cutting off the communication between chambers 50, and 52.

Referring now to Fig. VI, it will be seen that the vacuum no longer would exist in chamber 50, if the valve 60, were closed, and therefore the pneumatic 28, would open under tension of spring 24, and the valve stem 118, would also drop by its own weight carrying disks 125, and 126, with it. As hereinbefore explained, the opening of the pneumatic 28, causes the damper 7, to be raised from the striking level of the hammers. The above reasoning would also hold good for the treble section of the device. It is now obvious that the operation of the dampers is now placed at the will of the operator, by whom they can be manually controlled by the use of said levers 180, and 181.

Having thus described my invention, I claim:

1. The combination, with the strings and hammers, and with pneumatic playing mechanism for said hammers, including a tracker-board and perforated sheet; of a movable damping device adapted to be temporarily interposed between the hammers and strings; pneumatic actuating mechanism for shifting said damping device; and pneumatic actuating means whereby said actuating mechanism may be controlled by auxiliary perforations in said sheet.

2. The combination, with the strings and hammers, and with pneumatic playing mechanism for said hammers, including a tracker-board and perforated sheet; of a plurality of movable damping devices adapted to be temporarily interposed between the

hammers and strings, in selected groups; a plurality of pneumatic actuating mechanisms for independently shifting the several damping devices; and pneumatic actuating means whereby said actuating mechanisms may be respectively controlled by independent groups of auxiliary perforations in said sheet.

3. The combination, with the strings and hammers, and with pneumatic playing mechanism for said hammers, including a tracker-board and perforated sheet; of a movable damping device adapted to be temporarily interposed between the hammers and strings; pneumatic actuating mechanism for shifting said damping device; pneumatic actuating means whereby said actuating mechanism may be controlled by auxiliary perforations in said sheet; and pneumatic actuating means whereby said actuating mechanism may be manually controlled by the operator.

4. The combination with strings and hammers, and with pneumatic playing mechanism for said hammers, including a tracker board and perforated sheet; of a movable damping device adapted to be temporarily interposed between the hammers and strings; pneumatic actuating mechanism for shifting said damping device, including a main valve; and a pneumatic actuating means including an auxiliary valve controlled by perforations in the sheet for operating said main valve.

5. The combination with strings and hammers and with pneumatic playing mechanism for said hammers including a tracker board and perforated sheets; of a movable damping device adapted to be temporarily interposed between the hammers and strings; pneumatic actuating mechanism for shifting said damping device, including a main valve; a pneumatic actuated means including an auxiliary valve controlled by perforations in the sheet for operating said main valve; and pneumatic actuating means whereby said actuating mechanism may be manually controlled by the operator.

In testimony whereof, I have hereunto signed my name, at Philadelphia, Pennsylvania, this fifteenth day of May, 1908.

PHILIP WUEST, JR.
